SIGNAL SWITCH

Harry C. Rowe, Chicago, Ill., assignor to Nutone,
Incorporated, Chicago, Ill., a corporation of New
York

Application October 15, 1947, Serial No. 779,899

6 Claims. (Cl. 200—37)

1

This invention relates to electric signaling devices and is directed particularly to improvements in a motor driven control switch which is adapted to be used in conjunction with signals of the multiple chime type, for sounding a series of tones upon operation of a signal control button.

The conventional multi-chime signal unit, of the type used frequently in homes, consists of a number of signal or sound producing elements, solenoids or electromagnetic strikers, for energizing the signal units serially or successively, and, usually a motor driven control switch by which the solenoids, or strikers, are energized in a progressive predetermined sequence. The conventional chime usually contains three or four elongated chime tubes as the signal elements, and these chromatically are tuned to produce a pleasant sequence of notes when struck in predetermined order. Repeat actuation of the push button will cause a repetition of the notes through a successive cycle of operation of the motor operated switch.

The principal objective of this invention has been to provide a simple, inexpensive motor operated switch which, selectively during a cycle of operation, is effective to produce different numbers of notes or sounds in repetitive order or in different order. Thus, used in conjunction with a four element signal, the switch may be set conveniently to cause only four notes in succession to be sounded upon each operation of the push button controller, or the switch may be set to cause four notes to be sounded in succession, followed by a repeat cycle, of one to four notes, depending upon the number of contacts used in the switch. In the alternative, the contacts may be arranged to sound only two or three notes selectively, or two or three notes, followed by a succession of two or three or four notes, depending upon the sound effect which is most desirable to the user. The number of notes sounded will depend, of course, upon the number of contacts utilized in the switch.

In this manner, a single motor driven switch may be adjusted conveniently to cause energization of all of the notes of a chime or signal element, or to cause a repetitive succession of such notes as desired.

The switch of the invention in the preferred construction comprises a motor, having a suitable gear reduction train, a contact arm, and a contact panel, which is made in sectors. These sectors carry contacts which are in circuit connection with solenoids or electromagnetic strikers of

2

the signal unit, but one or both sectors are relatively shiftable into or out of the path of movement of the contact arm. Hence, if all contacts are in the path of movement, circuits are completed through all of the contacts as the arm sweeps over the contacts successively, and a series, or a double series of notes will be sounded, according to the circuit connections of the contacts with the respective electromagnetic strikers. If one or the other of the sectors is shifted out of the path of movement of the contact arm, then only those contacts remaining in the path of movement will be energized, and notes will be sounded in accordance with the circuit connection of such contacts with the respective electromagnetic actuators. Thus, the apparatus, by way of example, may embody two sectors, each having four contacts. When both sectors are in position for operative engagement of the contact arm with the contact on the sectors, four notes will be sounded, followed by four other notes, but when the shiftable sector is moved into non-operative position, four notes only will be sounded, after which the contact arm will move to its starting position and then stop to await re-energizing of the motor through the push button. It is apparent that a wide variety of note sequences, or repetitions, may be obtained using additional sectors or various arrangements of contacts on the sectors.

From the foregoing principles upon which the invention is based, and the following detailed description of the drawings in which a typical embodiment of the improvement is illustrated, those skilled in the art readily will comprehend the various modifications to which the invention is susceptible.

In the drawings:

Figure 1 is a side elevation of the switch and motor unit of the invention.

Figure 2 is a top elevational view of the switch and motor unit.

Figure 3 is a sectional view of the switch taken along line 3—3 of Figure 1.

Figure 4 is a front elevational view showing the switch panel sectors both in operative positions, and so arranged that more than one series of notes are sounded.

Figure 5 is a view similar to Figure 4 with one of the switch sectors out of operative position whereby only one series of notes is sounded.

Figure 6 is a diagrammatic representation of a rotor control disc of the units and its attendant brushes when the rotor disc is in an inoperative position.

Figure 7 is a diagrammatic representation of the rotor disc and brushes after the disc has begun to revolve.

Figure 8 is a diagrammatic representation of the rotor disc and switch panel showing the contacts in operative engagement with a contact carried on a sector of the switch.

Figure 9 is a diagrammatic representation similar to Figure 8 but with one sector moved to inoperative position.

Figure 10 is a diagrammatic representation of the wiring arrangement of the switch and one representation wiring diagram of the circuits between the switch contacts and related electro strikers.

The drive motor and gear reduction apparatus which furnishes the power for the switch may be of conventional construction and therefore is not shown in detail. Essentially this portion of the apparatus, indicated generally at 10, comprises a field coil 11 and pole pieces 12 which surround a rotor housing 13. The rotor contained within the housing is in driving connection with the gear reduction unit enclosed within a casing 14, the reduction unit being constructed to translate the relatively high speed of the motor to a suitable slow speed for operation of the switch. The motor and gear reduction unit is fastened to a base plate 15 by means of spacers 16 and screws 17.

The switch assembly, to which the present invention is directed, is mounted upon the base plate 15, on the side opposite the motor and gear reduction unit. This switching assembly comprises sectors 18 and 19 carrying signal circuit contacts indicated generally at 20, a rotor or control disc 21, a contact arm 22 which, in the embodiment shown, is fabricated as a part of the assembly of the control disc 21, and a pair of brushes 23 and 24 which cooperate with the control disc 21. Brushes 23 and 24, in conjunction with the control disc 20, constitute a holding circuit through which the motor is energized after initial energization through a push button controller or the like. The switch arm 22 on the other hand serves the contacts 20 through which signal strikers may be energized.

The contact carrying sectors 18 and 19 are relatively shiftable into and out of the circular path of movement of the contact arm 22. In the embodiment shown, a construction satisfactory for simple commercial purposes is provided by pivotal mounting of only one of the sectors 19, about a pivot 25 while the other sector 18 is stationary. The sectors meet along a circular line 26 which is concentric with respect to the axis of rotation of the arm 22 inwardly of the annular row of contacts which are carried by the sector 19. Hence if the sector 19 is shifted outwardly, as shown in Figure 5, its contacts are removed from the path of movement of the contact arm 22.

The details of construction of the elements utilized for maintaining a circuit to the motor throughout a cycle of operation thereof are shown mechanically in Figures 1 and 3 and diagrammatically in Figures 6, 7 and 10. For this purpose brushes 23 and 24 are fastened to opposite sides of an insulator block 28 which in turn is secured to the base plate 15 by means of a screw 29. These brushes at their forward end are configurated to ride the periphery of control disc 21 while the opposite ends of the brushes are provided with terminals 30 to which lead wires 31 are soldered. Control disc 21 is seated upon the counter-turned portion of a bushing 32 and is fastened to the bushing by spinning over the end of the counter-

turn portion. The bushing, in turn, is mounted upon a stub shaft 33 extending from the gear train 14, the shaft passing through a suitable clearance opening in the base plate 15. Disc 21, as shown best in Figures 6 and 7, has a gap in its periphery which is so dimensioned in width that contact with brush 24 is avoided when the disc reaches a position of alignment. Hence, a circuit to the motor is completed through brushes 23 and 24 when both are in engagement with the periphery of disc 21, and the circuit is disrupted as the gap passes one of the brushes 23. The brushes are spaced relatively close adjacent to one another so that the rotor by inertia will continue to rotate until it reaches a position of alignment with the other brush 24.

The details of construction of the contact sectors are shown best in Figures 1, 2, 4 and 5. As previously indicated, in the embodiment shown, the sector 18 is stationary and is mounted by means of screws 35 upon spacers 36 which in turn project from the base plate 15. Movable contact sector 19 is riveted as at 25, to the stationary sector 18. The movable sector has a lever arm 37 fixed to it by rivets 38 and this lever arm projects beyond the sector, terminating in a handle portion 39 which rides within a slot 40 provided in the base plate 15. For the purpose of retaining the movable sector in closed position a spring clip 41 projects from the stationary sector 18 and terminates in a detent portion 42 which engages an edge of a slot 44 cut into or through the movable sector 19. A leaf (not shown) may be mounted upon the stationary sector 18 just beneath the spring clip 41 to support the movable sector 19 against the pressure of the spring clip.

Stationary sector 18 is equipped with contacts 20 arranged in an annular row concentric with the axis of rotation of the control arm 22. This control arm is fastened by means of a rivet 45 to the control disc 21, but is sprung from the plane of the control disc for resilient engagement with the contacts 20 so as to sweep them during its rotation. In the preferred construction, control arm 22 has two buttons near its end, one 43, for engaging the contacts 20 and the other 46 for riding upon the surface of the sector 18 when the sector 19 is swung out of the way.

Like the sector 18, sector 19 also has contacts 20 so positioned that they are in the path of movement of the arm 22 so as to be engaged by contact button 43 thereof when the sector 19 is in closed position as shown in Figure 4. Thus the support of the contact arm is accomplished by button 46 which rides upon the surface of the stationary sector when the movable sector is not in position to afford support, as shown in Figures 8 and 9.

A typical signal circuit of the type which the switch of the present invention is adapted to serve is shown in Figure 10. This representatively comprises four solenoids or electromagnetic actuators 50, 51, 52 and 53, each positioned when energized to sound its respective chime or signal element 54. The winding of the motor 10 is energized from leads 55 and 56, these leads being taken respectively to the terminals of the brushes 23 and 24, and a push button switch, 57, has its terminals in short circuiting connection with the brushes 23 and 24 through leads 58 and 59. Thus, when the push button switch is closed while brush 24 is in alignment with the gap in rotor disc 21, a circuit is established to lead 55 through brush terminal 23 to lead 59 through the switch 57 and back through lead 58 to the input lead 56. In

consequence the motor operates, driving disc 21 to a point where both brushes engage it and complete the circuit through it, whereupon the motor continues to operate until the circuit is disrupted through subsequent alignment of the gap in the disc with brush 23, followed by overtravel to bring the gap in alignment with brush 24.

In the signal switching circuit, arm 22 is driven by the motor into successive engagement with contacts 20 of the first sector, and then into engagement with the contacts of the second sector if the latter is in closed position. As shown in Figure 10 one terminal of each of the solenoids 50 to 53 inclusive is in respective connection with the contacts 20 of the stationary sector through the leads 60, 61, 62 and 63 respectively. The other terminals of the solenoids 50 to 53 inclusive are in connection with the common feeder 64 which is connected through a line 65 to the input terminal 55. Lead 65, if desirable, may contain a resistor 66 for adjustment of tone volume. Contact arm 22, being in electrical connection with disc 21, is energized through brush 24 from the input terminal 56, and as contact arm 22 sweeps past the respective buttons 20 solenoids 53, 52, 51 and 50 successively are energized. The contacts 20 on the movable sector 19 are energized through flexible terminals 67 (Figure 4) taken to the respective leads 61, 62 and 63. Thus when sector 19 is in closed position contact arm 22 causes the solenoids to be energized in a second succession of notes or in a different succession of notes depending upon the manner in which the contacts of the second series are connected to the contacts of the first series.

The wiring diagram shown in Figure 10 is representative only and those skilled in the art will readily comprehend various modifications which may be utilized to produce different numbers of notes or note sequences depending upon the number of contacts and the relative interconnection of the contacts utilized in the respective sectors. For instance, one sector may have more or less contacts than the other, in which event different combinations and numbers of notes may be sounded in a complete cycle of revolution of the contact arm. The apparatus in a simple inexpensive manner enables the house holder or user to select the type of signal which is most pleasing or useful for his purposes.

Having described my invention, I claim:

1. An electrical switch for controlling the cyclic operation of chimes comprising; a rotatable shaft, a contact arm carried by the shaft, a panel disposed in a plane normal to the axis of the shaft, a series of contact elements fixed on the panel and disposed concentrically with respect to the axis of said shaft in a circle normally to be wiped by said contact arm, the said contact elements on the said panel being adapted for electrical connection with means for sounding a sequence of chimes, said panel being divided into sectors with a portion of the said series of contact elements on each sector, one of said sectors being in fixed relationship with respect to said shaft, and at least one other of the said sectors being pivotally mounted and adapted to be shifted with respect to the shaft, whereby in the shifted position the contact elements carried by the pivotally mounted sector are out of position to be wiped by the said contact arm.

2. In combination with an electric motor and a speed reduction unit mounted in a frame, and a shaft adapted to be driven by said motor through said speed reduction unit, an electric switch for

controlling the cyclic operation of chimes comprising; a control member mounted on the shaft, said member adapted to effect cyclic operation of the motor, a contact arm adapted to rotate with the shaft, a sectional panel mounted on the frame in a plane normal to the axis of the shaft, a series of contact elements fixed on said panel in a circle concentric with the axis of the shaft in a position to be wiped normally by said contact arm, the contact elements being adapted for electrical connection with means for sounding a sequence of chimes, one sector of the sectional panel being fixed to the frame and another sector of the panel being pivotally journaled on the frame, each sector having fixed to it a portion of the series of contact elements, with the pivoted sector being adapted to be moved to a position in which the contact elements fixed thereon are out of position to be wiped by the said contact arm.

3. An electric switch comprising; a frame, a panel mounted on the frame, a rotatable shaft having its axis of rotation disposed on a line normal to the panel, a contact arm carried by the shaft and extending radially therefrom, a series of contact elements fixed on the panel and disposed concentrically with respect to the axis of the shaft in a circle to be wiped normally by the contact arm, said panel being divided into sectors with a portion of the series of contact elements on each sector, one of said sectors being in fixed relationship with respect to the frame, and at least one other of the said sectors being pivotally mounted on the frame and adapted to be shifted away from the shaft, whereby in the shifted position the contact elements carried by the pivotally mounted sector are out of position to be wiped by the said contact arm.

4. An electric switch comprising; a frame, a panel mounted on the frame, a rotatable shaft having its axis of rotation on a line normal to the panel, a contact arm carried by the shaft and extending radially therefrom, a series of contact elements fixed on the panel and disposed concentrically with respect to the axis of the shaft in a circle to be wiped normally by the contact arm, said panel being divided into sectors with a portion of the series of contact elements on each sector, one of said sectors being in fixed relationship with respect to said shaft, at least one other of the said sectors being pivotally mounted and adapted to be shifted away from the shaft whereby in the shifted position the contact elements carried by the pivotally mounted sector are out of position to be wiped by the said contact arm, said fixed sector having a continuous surface in a circle concentric with respect to the axis of the shaft but inwardly of the circle to be wiped by the contact arm, for supporting said contact arm when said pivotally mounted sector is shifted out of position to be wiped by said contact arm.

5. An electric switch comprising; a frame, a panel mounted on the frame, a rotatable shaft having its axis of rotation disposed on a line normal to the panel, an electric motor for driving said shaft, circuit means for energizing the motor, including a normally closed motor energization control member associated with said rotatable shaft, said member being adapted to open the circuit at the end of each revolution of the shaft for deenergizing the motor, a contact arm carried by said shaft and extending radially therefrom, a series of contact elements fixed on the panel and disposed concentrically with respect to the axis of the shaft in a circle

normally to be wiped by the contact arm, said panel being divided into sectors with a portion of the series of contact elements on each sector, one of said sectors being in fixed relationship with respect to said shaft, and at least one other of said sectors being pivotally mounted and adapted to be shifted away from the shaft to a position in which it is beyond the circle of revolution of said contact arm.

6. In combination with an electric motor, an electric switch for controlling the cyclic operation of chimes comprising; a shaft adapted to be rotated upon energization of the motor, circuit means for energizing the motor including a control member carried by said shaft adapted to maintain energization of the motor during substantially a full revolution of the shaft and thereafter effect deenergization of the motor for stopping the rotation of the shaft after it completes a full revolution, a contact arm carried by the shaft, a panel disposed in a plane normal to the axis of the shaft, a series of contact elements fixed on the panel and disposed concentrically with respect to the axis of said shaft and within the arc to be wiped by said contact arm

7 during that portion of the revolution of the shaft when the energization of the motor is being maintained by the control member, the said contact elements on the panel being adapted for electrical connection with means for sounding a sequence of chimes, said panel being divided into sectors with a portion of the said series of contact elements on each sector, one of said sectors being in fixed relationship with respect to the shaft and at least one other of the said sectors being pivotally mounted and adapted to be shifted with respect to the shaft, whereby in the shifted position the contact elements carried by the pivotally mounted sector are out of position to be wiped by the said contact arm.
